UNITED STATES PATENT OFFICE.

FRED W. SUTHERLAND, OF KALAMAZOO, MICHIGAN.

MACHINE FOR AND METHOD OF SEALING WAXED CARTONS.

1,316,120.

Specification of Letters Patent. Patented Sept. 16, 1919.

Application filed April 30, 1919. Serial No. 293,795.

To all whom it may concern:

Be it known that I, FRED W. SUTHERLAND, a citizen of the United States, residing at Kalamazoo, Michigan, have invented certain new and useful Improvements in Machines for and Methods of Sealing Waxed Cartons, of which the following is a specification.

This invention relates to improvements in machines for and methods of sealing waxed cartons.

In the manufacture of cartons, it has not been found practical so far as the applicant has been able to discover to seal or join by glue or other adhesives, even when the adhesive is specially prepared for the purpose, cartons which have been previously waterproofed by an application of paraffin wax or the like.

20 The main objects of this invention are:

First, to provide an improved machine for sealing waxed cartons by means of which the parts of such cartons are effectively joined by glue.

25 Second, to provide an improved method of sealing waxed cartons.

Further objects, and objects relating to structural details, will definitely appear from the detailed description to follow.

30 I accomplish the objects of my invention by the devices and means described in the following specification. The invention is clearly defined and pointed out in the claims.

35 A structure which is a preferred embodiment of my invention is clearly illustrated in the accompanying drawing forming a part of this specification, in which:

Figure I is a detail side elevation of a 40 sealing machine embodying the features of my invention, portions of the frame being shown in vertical section and other parts of the mechanism being shown conventionally.

Fig. II is a detail plan view of the feed 45 conveyer of my improved sealing machine, partially in section on a line corresponding to line 2-2 of Figs. I and III.

Fig. III is an enlarged detail vertical section on a line corresponding to line 3-3 of 50 Fig. I.

Fig. IV is a detail transverse section on a line corresponding to line 4-4 of Fig. I, showing details of the glue applying mechanism.

55 Fig. V is a detail transverse section on a

line corresponding to line 5-5 of Fig. I, showing details of the folding mechanism.

Fig. VI is a detail transverse section on a line corresponding to line 6-6 of Fig. I, showing further details of the folding 60 mechanism.

Fig. VII is a detail transverse section on a line corresponding to line 7-7 of Fig. I, showing details of the pressing means.

In the drawing, similar reference characters refer to similar parts throughout the several views, and the sectional views are taken looking in the direction of the little arrows at the ends of the section lines.

Referring to the drawing, 1 represents the 70 frame of the machine, at the front of which is a hopper 2 having delivery rollers 3. These rollers deliver the cartons to the feed conveyer comprising a series of supporting belts 4 supported by pulleys 5 and a pair 75 of upper presser belts 6 supported by rollers 7 at their ends. This conveyer carries the cartons 8 along in the flat with their edges 9 and 10 projecting at the sides of the outer feed belts. The edge 9 is the sealing flap which is adapted to be lapped upon the opposite edge 10.

My improvements are especially designed for the sealing of paraffin waxed cartons. Heretofore, this has not been found practical on account of the fact that the glue would not penetrate or adhere to the surfaces to be joined, so that the joints formed were insecure and not practical, even when specially prepared glue was employed. I use 80 the term glue in its comprehensive sense.

To prepare these surfaces to receive the glue and enable making a secure joint or connection between the parts to be joined, I direct jets of steam from nozzles 11 and 12 85 against the surfaces which are to receive the glue and coating surfaces which are to be lapped or brought face to face therewith.

By carrying the cartons along so that their edges project from the belts of the feed 100 conveyer the belts serve as guards for the remaining surfaces of the carton, that is, the steam jets are confined to the surfaces which it is desired to treat. The cartons are delivered from the feed conveyer through 105 the rollers 13 to the sealing conveyer consisting of the coating belts 17 and 18, the belt 19 and the coating rollers 20. As the cartons are carried along by the belts 17 and 18 the flaps 9 are brought into contact with 110

the glue roller 21 which applies the glue thereto.

After leaving the glue roll the carton is engaged by the rod-like folder members 22 which swing portions of the carton to an upright position as shown in Fig. V, where they are engaged by the turning belts 23 and turned over until they pass under the rollers 24—see Fig. VI, from which they pass 10 between the presser belts 27 and 28 from which they are discharged to the discharge table 29.

The details of the flap turning and folding means form no part of my present invention and therefore the same are conventionally shown and are not elaborated herein.

The machine described enables the efficient carrying out of my improved method which 20 consists in the driving off or removing the greater portion of the wax on the surfaces to be glued together by impinging jets of steam, hot air or other suitable means, applying the glue and pressing the surfaces together.

I have not attempted to illustrate various means or adaptations by which this may be carried out, but I have shown the same as I have embodied it in practical use in the manufacture of cartons, in one type of sealing machine.

By my improved method and apparatus, I am enabled to rapidly seal waxed cartons so that the joint is substantially as secure as though formed on untreated material.

Having thus described my invention, what I claim as new and desire to secure by Letters Patent is—

1. In a machine for sealing waxed cartons, 40 having a sealing flap at one edge adapted to be lapped upon the opposite edge, the combination of a carton feeding means comprising pairs of opposed belts between which the carton is carried in the flat with its 45 sealing flap and its edge upon which the flap is to be lapped projecting at the sides of the belts, steam nozzles disposed to deliver against the glue receiving surface of the projecting sealing flap and the coacting project- 50 ing surface at the opposite edge of the carton, said belts constituting guards for other portions of the carton, a sealing conveyer, a glue roll disposed at the side of said sealing conveyer to apply glue to the sealing flap as 55 the carton is carried along by the conveyer, and means at the rear of said glue roller for folding the carton with its glued flap and co-acting surface lapping.

2. In a machine for sealing waxed cartons 60 having a sealing flap at one edge adapted to be lapped upon the opposite edge, the combination of a carton feeding means comprising pairs of opposed belts between which the carton is carried in the flat with its sealing

flap and its edge upon which the flap is to be 65 lapped projecting at the sides of the belts, steam nozzles disposed to deliver against the glue receiving surface of the projecting sealing flap and the coacting projecting surface at the opposite edge of the carton, said belts 70 constituting guards for other portions of the carton, and means for applying glue to said flap and folding the carton with its glued flap and coacting surface lapping.

3. In a machine for sealing waxed cartons, 75 the combination of a carton feeding means comprising pairs of opposed belts between which the carton is carried in the flat with its surfaces adapted to be glued together projecting at the sides of the belts, steam 80 nozzles disposed to deliver against such surfaces, said belts constituting guards for other portions of the carton, a sealing conveyer, a glue applying means at the rear of said nozzles, and means at the rear of said glue 85 applying means for folding the carton.

4. In a machine for sealing waxed cartons, 90 the combination of a carton feeding means comprising pairs of opposed belts between which the carton is carried in the flat with its surfaces adapted to be glued together projecting at the sides of the belts, steam nozzles disposed to deliver against such surfaces, said belts constituting guards for other portions of the carton.

5. In a sealing machine, the combination 95 of a carton conveyer adapted to carry a carton in the flat with its surfaces adapted to be glued together projecting at the sides of the conveyer, steam nozzles disposed to deliver against such surfaces, said conveyer constituting a guard for the other portions of the carton, and means for applying glue and folding the carton, for the purpose specified.

6. In a sealing machine, the combination 100 of a carton conveyer adapted to carry a carton with its surfaces adapted to be glued together exposed, steam nozzles disposed to deliver against such surfaces, and means for applying glue and folding the carton, for the 110 purpose specified.

7. In a machine for sealing waxed cartons, 105 the combination of a carton conveying means, means for subjecting the surfaces adapted to be glued together to steam, and 115 means for applying glue and folding the carton.

8. In a machine for sealing waxed cartons, the combination of a carton carrier, 120 means for delivering a hot fluid against the coacting surfaces of the carton adapted to be glued together, and means for applying glue to such surfaces and pressing them together.

9. In a machine for sealing waxed car- 125 tons, the combination of a carton conveying means, means for removing or driving off a substantial portion of the wax from the

surfaces adapted to be glued together by directing jets of steam thereon, and means for applying glue and folding the carton.

10. In a machine for sealing waxed cartons, the combination of a carton conveying means, means for heating the surfaces adapted to be glued together, removing or driving off of a substantial portion of the wax thereon, and means for applying glue and 10 folding the carton.

11. The method of sealing waxed cartons consisting of removing a substantial portion of the wax from the surfaces to be glued together by impinging jets of steam thereon, 15 and applying glue to such surfaces and pressing them together.

12. The method of sealing wax cartons

consisting of removing a substantial portion of the wax from the surfaces to be glued together by impinging jets of hot fluid thereon, and applying glue to such surfaces and 20 pressing them together.

13. The method of sealing waxed cartons consisting of heating the surfaces to be glued together, removing a substantial portion 25 of the wax, applying glue thereto, and pressing such surfaces together.

In witness whereof I have hereunto set my hand and seal in the presence of two witnesses.

FRED W. SUTHERLAND. [L. S.]
